United States Patent Office.

JAMES O. ALTICK, OF DAYTON, OHIO, ASSIGNOR TO HIMSELF AND
GEORGE W. HOLGEN, OF THE SAME PLACE.

Letters Patent No. 62,989, dated March 19, 1867.

IMPROVEMENT IN GRAPE AND OTHER ARBORS.

The Schedule referred to in these Letters Patent and making part of the same.

TO ALL WHOM IT MAY CONCERN:

Be it known that I, J. O. ALTICK, of Dayton, in the county of Montgomery, and in the State of Ohio, have invented certain new and useful Improvements in the Construction of Grape or other Arbors, and do hereby declare that the following is a full, clear, and exact description thereof, reference being had to the accompanying drawings, and to the letters of reference marked thereon, making a part of this specification.

My invention consists in the application and construction of metallic casting, so cast as to suit the form of the grape arbor, and connect the vertical posts and top rails without bending the timber, and at the same time forming a neat and economical ornament.

In the annexed drawings, B B represent the vertical posts of a grape or other arbor, having the ordinary shape, and C, running at suitable distances apart, horizontally, at the sides and top. E E represent the stays or scantling at the top of the arbor, and upon which the slats C at the top are also nailed. Connecting the posts B and scantling E are the metallic castings A. These castings may be either plain, as shown in Figures 1 and 2, or may be ornamented, as represented in Figure 3. Each casting is cast to suit the curve at the top of the arbor, and has a cup, b b, in each end for the insertion of post B and stay E. At a point, x, about the centre of the curved back of the casting, are formed ears, with suitable openings to connect the casting to the slot, as shown in fig. 1.

This invention obviates the necessity of bending the timber to form the top of the arbor in a symmetrical shape, and gives the arbor a neat appearance.

Having thus fully described my invention, what I claim as new, and desire to secure by Letters Patent, is—

The metallic casting A, constructed substantially as described, and used for the purposes herein set forth. In testimony that I claim the foregoing, I have hereunto set my hand and seal this eleventh day of December, 1866.

JAMES O. ALTICK.
